BALANCE SCALE

George R. Stehl, Stoney Brook, N.Y., assignor, by mesne
assignments, to Xerox Corporation, Rochester, N.Y.

Filed May 14, 1968, Ser. No. 11,928

Term of patent 14 years

Int. Cl. D10—99

U.S. Cl. D52—10

FIG. 1

FIG. 2

FIG. 3

FIG. 1 is a side-back perspective view of my design for a balance scale.

FIG. 2 is an enlarged fragmentary back elevational view of the fulcrum, bearing, indicator portion of the balance scale.

FIG. 3 is a side-front perspective view taken diametrically opposite the FIG. 1 view.

I claim:

The ornamental design for a balance scale, as shown.
